(57) **CLAIM**

The ornamental design for a tire traction device, as shown and described.

DESCRIPTION

FIG. 1 is a perspective view of a tire traction device showing my new design in use with a tire and wheel combination; FIG. 2 is a perspective view of a tire traction device removed from the tire and wheel combination;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

In the drawings, the broken lines showing a tire and wheel combination illustrate environment and form no part of the claimed design.

The tire traction device is shown on an enlarged scale in FIGS. 2-8.
